UNITED STATES PATENT OFFICE.

JAMES MORTON COLMAN, OF PORT TOWNSEND, WASHINGTON.

WATER-TUBE BOILER.

SPECIFICATION forming part of Letters Patent No. 774,564, dated November 8, 1904.

Application filed February 20, 1904. Serial No. 194,491. (No model.)

To all whom it may concern:

Be it known that I, JAMES MORTON COLMAN, a citizen of the United States, and a resident of Port Townsend, in the county of Jefferson 5 and State of Washington, have invented a new and Improved Water-Tube Boiler, of which the following is a full, clear, and exact description.

My invention relates to water-tube boilers. 10 The objects of my invention are to increase the efficiency and at the same time decrease the cost of manufacture and maintenance of boilers of the character mentioned.

Further objects of my invention will appear in the course of the subjoined description.

Reference is to be had to the accompanying drawings, forming a part of this specification, in which similar characters of reference indicate corresponding parts in all the figures.

20 Figure 1 is a front view of my improved boiler with parts of the casing removed in order to show interior construction. Fig. 2 is a side view of the same, also showing interior construction. Fig. 3 is a rear view, 25 and Fig. 4 is a sectional view on the line 4-4 of Fig. 2.

In the drawings, 1 represents a foundation of any desired construction.

2 represents a series of water-pipes laid in 30 cement upon the foundation to keep the heat from unduly heating the foundation parts and burning out the timbers, and above the water-pipes is a layer of brick 3, which forms the bottom of the ash-pits 5. Columns 4 extend upwardly from the foundation for supporting the parts, as will be seen. In the ash-pits are placed shaking-grates 6.

7 is a cast-iron arch for the fire-doorway, and 8 is a division-wall between the furnaces, 40 which supports upon its top a pipe 9 for the admission of air to support combustion.

10 is a cast-iron furnace front.

11 is a lower header, and 12 an outside casing provided with an asbestos lining 13. This casing is provided with longitudinal seams 14 on the outside, arranged for easy access in case of repairs, and it is also provided with a series of holes 15, through which the soot may be blown out. Each hole has a short piece 50 of tube expanded into it and projecting out-

wardly. A cap is secured to the end of the tube and has to be removed when the soot is blown out. Side tubes 16 are provided extending along each side of the boiler, as shown. Within the casing are stationed a plurality of 55 headers 17, arranged in tiers at the front and back of the boiler. These headers and side tubes are joined together by short tubes 18, as shown. The water-tubes of the boiler are represented at 19. They extend into the headers 60 by being bent at their ends 20, as shown in Fig. 2. These headers are also provided with manholes 21. Upon the top of the boiler is a steam-dome 22, provided with a manhole 23 and connected to the parts below by the passages 24 and 25. This dome is provided with ports 26 for connection with the external piping.

27 is the top of the uptake and smoke-stack. 70 The water-tubes run from back to front and are expanded into the headers in the same manner that tubes are secured in a shell-boiler. The headers and side pipes are of the same size and large enough to permit a workman to go inside for the purpose of repairing the parts 75 and are provided with longitudinal riveted seams 28 29.

It will be seen from an examination of this construction that a very compact and strong boiler is obtained; that no stay-bolts are necessary and no threaded joints; that there are no hand-holes, and that the boiler carries a greater quantity of water than the forms heretofore known, thereby securing more steady steam; that complete and ready access is secured to 85 every part of the boiler for cleaning and repairing; that perfect facility is obtained for separating water from steam, thereby insuring economy; that the circulation is ample to carry off all steam, there being a very large 90 area in the circulation parts; that a large grate area may be obtained to burn any kind of fuel; that no special fittings are required that must be obtained from a manufacturer, so that any boiler-maker can repair the parts, and that perfect facilities for blowing out soot are secured.

Having thus described my invention, I claim as new and desire to secure by Letters Patent—

1. In a water-tube boiler, the combination of a series of headers, water-tubes secured 100

thereto, a steam-dome above the same communicating with one of said headers, means for permitting circulation from each of said headers to the others, said means comprising 5 transverse side pipes, and means for heating the headers and the water-tubes.

2. In a boiler, the combination of a series of headers communicating with each other, tubes extending into the walls of said headers, a series of side tubes each communicating with the ends of two of said headers, and a steam-dome communicating with one of said headers.

3. In a boiler, the combination of a series 15 of water-tubes, a series of headers circular in cross-section, said tubes extending in a slightly inclined direction being bent at their ends and passing radially through the side walls of two of said headers, and a steam-dome communicating 20 with one of said headers.

4. In a boiler, the combination of a plurality of headers at each end of the boiler, a plurality of side pipes each connecting two of said headers and substantially the size of said headers, tubes connecting each of said headers to another header and each of said side pipes to another side pipe, and a steam-dome connecting to one of said headers.

5. A boiler comprising a header at each end 30 thereof, and a transverse side pipe connecting the ends of said headers.

6. A boiler comprising a plurality of parallel headers at each end thereof, and a plurality of side pipes connecting said headers.

35 7. A boiler comprising a plurality of parallel headers at each end thereof, a plurality of side pipes connecting said headers, and a series of water-tubes between the side pipes and entering the headers.

40 8. A boiler comprising a casing, a series of headers therein running parallel to the casing, and means for blowing out soot, said means

being located between said headers in the walls of said casing.

9. A boiler comprising a vertical series of 45 headers, water-tubes, side pipes and a steam-dome in communication with said headers and located parallel therewith.

10. A boiler comprising a series of headers on each end thereof, the headers of one series 50 being slightly above those of the other, tubes connecting the headers of each series, and a steam-dome connected directly with the highest header.

11. In a water-tube boiler, the combination 55 of a series of headers, water-tubes connected thereto, a steam-dome above and communicating with one of said headers, means for permitting circulation from each of said headers to the others, said means comprising transverse parallel side pipes of substantially the size of said headers, and means for heating the headers and the water-tubes.

12. In a water-tube boiler, the combination 60 of a series of headers on each end of the boiler, water-tubes connected to said headers, a series of parallel side pipes each connected to headers at its ends, and means for heating said elements.

13. In a boiler, the combination of a series 70 of headers at each end of the boiler, the headers of one series being slightly above those of the other series, and a series of parallel water-tubes extending in a slightly-inclined direction and having bent ends passing radially through 75 the side walls of a header of each series.

In testimony whereof I have signed my name to this specification in the presence of two subscribing witnesses.

JAMES MORTON COLMAN.
